COMBINED TABLE AND MULTIPLE CHAIR UNIT
FOR STUDENT INSTRUCTION

James W. Cooper, 611 S. N St.,
Indianola, Iowa 50125

Filed May 11, 1966, Ser. No. 2,251

Term of patent 14 years

(Cl. D33—14)

FIG. 1 is a perspective view of a combined table and multiple chair unit for student instruction showing my new design;

FIG. 2 is a top plan view; and

FIG. 3 is a side elevation view thereof.

I claim:

The ornamental design for a combined table and multiple chair unit for student instruction, substantially as shown.
